Arthur D. Marr
ATTORNEY

UNITED STATES PATENT OFFICE.

JOHN M. CLARK, OF NEW YORK, N. Y.

FLAME PLUG FOR INTERNAL-COMBUSTION ENGINES.

Application filed October 2, 1923. Serial No. 666,184.

The device, the subject of this invention is termed a flame plug to differentiate it from the commonly known spark plugs and to emphasize its action and the results obtained from its use.

The principal object of the invention is to provide a hot and intense flame, rather than a mere spark.

To provide step-up means within the plug 10 casing and in direct communication with the combustible gases within the cylinder of the engine, which so intensifies the current passing that a long and retained flame passes from the final step-up element to the ground 15 portion of the plug.

To provide a plurality of intermediate steps, each of which produces a spark of increasing intensity and to locate the final discharge flame at a point in relation to the 20 compressed fuel that will assure a thorough ignition of the fuel.

And a still further and important object of the invention is to locate the ignition flame at a point below the stratification line 25 and at a point where, by experiment it has been discovered, will be found the richest and therefore most readily combustible gases.

All of these objects and the means for 30 accomplishing them will be set forth in the specification which follows and the accompanying drawing should be referred to for a complete understanding of the specification.

In the drawing:—

Fig. 1 is a vertical, sectional view of the preferred construction.

Fig. 2, a sectional view through the intensifying member.

Fig. 3, a sectional view, similar to Fig. 1 and showing a different mode of construction.

Fig. 4 is a sectional view on the line 4—4 of Fig. 2.

Fig. 5 is a sectional view through an intensifier wherein blocks are used in lieu of rings.

Fig. 6 is a similar view, wherein bolts are used in lieu of blocks.

Fig. 7 is a view similar to Fig. 1, showing a built up intensifier.

Fig. 8 is an enlarged elevation of the intensifier shown in Fig. 7.

Fig. 9 is an end elevation of the device 55 shown in Fig. 7.

Similar reference numera's indicate like parts in all the figures where they appear.

At 10, I show a cast metal member which serves as a means for securing my plug into the cylinder of an engine and also is a means 60 for supporting the other portions of the plug.

One function of the member 10 is to serve as one side of the electric circuit; the member 10 may be referred to as the grounded 65 side of the circuit and is provided with an inwardly projecting flange 11, which is spaced a suitable distance from the intensifier, which is arranged centrally within the member 10 and the end of which passes through 70 a perforation 12 in the flange 11.

Within the member 10, I provide a chamber 13 which will be referred to later.

A small plug 14 may be screw-threaded into the member 10 and supports a plug of 75 insulation 15 and an insulating core 16. Through the plug 15 and core 16, a screw-threaded stud 17 passes and upon which I arrange a thumb nut 18 and a locking nut and washer 18 for securing the stud within the 80 plug and for securing a wire terminal to the stud.

As shown in Fig. 2, the stud 17 is provided with a liberal head 20, into which is screw-threaded a bolt 21 and upon the bolt 21, I arrange mica or other suitable insulating material as shown at 22 and in recesses in the insulating material, I secure rings 23 of which any suitable number may be provided. In the drawing, I have shown 85 seven such rings, but the number may be changed, if desired. These rings are each isolated from each other though I call particular attention to the fact that each ring projects outwardly beyond the adjacent insulating material 22. The first or innermost ring is in direct electrical contact with the head 20 of the stud 17, the member 24 shown on the bolt 21, serving as a lock nut to secure the rings and mica assembled. 90

I call particular attention to the fact that the head of the bolt 21 is small and that the insulating material tapers toward the bolt head as shown at 24, so as to isolate the bolt head and to prevent a spark jumping over 95 the bolt head to the flange 11.

In the construction shown in Figs. 3, 5 and 6, the insulating member 26 is formed of porcelain, as is the member 27 passing through the metallic members 10 and 14. I 110

prefer the use of porcelain and in the construction shown in Fig. 3, the rings 28 are snap or split rings as shown in Fig. 4.

The functions of my device can be fully obtained if blocks, bolt heads or studs are employed in lieu of the rings 23 or 28 shown. In Fig. 5, I show blocks 29 and 30 secured together in opposite pairs by a pin 31 which may be riveted within the blocks 29 and 30, 10 the first pin 32 extending through the stud 33 upon which the thumb nut 34 is screw-threaded.

The use of porcelain obviates the possibility of a spark jumping from the bolt head 15 as shown at 21 to the ring 11, forcing all of the current to pass from block to block or ring to ring, to its final destination, the grounded flange 11.

In Fig. 6, I show studs 35 passing through 20 the porcelain member 26 and each provided with a nut 36, the uppermost or innermost parts passing through the stud 33.

In the construction shown in Figs. 7 and 8, 25 the insulating member is oblong and flat and may be made of mica. This insulating member 37 is in this instance, a built up member provided with a plurality of studs, each insulated over the other, but each secured in the laminated and insulating member 37. In this instance, the studs 38 are in staggered relation and the end terminal is a pin as shown at 39. The screw 40 secures the device to a reduced portion of the stud 41 to which the thumb nut 42 is screw-threaded and a second screw thread 43 secures the pin 39 in place, the screws 40 and 45 entering into and serving as elements for the travel of the spark.

From the somewhat brief description of 40 the device here shown, its operation will be fully understood. I desire to call attention, however, to the fact that the travel of the spark from ring to ring or stud to stud will increase its intensity at the flange 11, a long 45 drawn out, 'fat' spark or flame will be produced.

I further call attention to the fact that the rings or blocks are in each instance arranged in a chamber 13 which serves as a 50 primary ignition chamber and further serves as a heat retaining means assuring that

sufficient heat will be retained to burn up the carbon that might otherwise collect on the rings or blocks. It will be noted that this chamber is in direct communication with the 55 interior of the cylinder.

Modifications other than those shown may be made without the scope of the appended claims without departing from the principle or sacrificing the advantages of this invention.

Having carefully and fully described my invention what I claim and desire to obtain is:—

1. A flame plug for internal combustion 65 engines comprising a metallic body member having a chamber therein and in direct communication with the interior of the cylinder of an engine and an intensifying means within said chamber, said intensifying means comprising an insulating member having a metallic supporting stem, a plurality of metallic members upon said insulating member and spaced thereon, the innermost metallic member being electrically connected to said 75 stem and a flange upon said body member and adjacent to the outermost metallic member.

2. A flame plug for internal combustion 80 engines comprising a metallic body member having a chamber therein and in direct communication with the interior of the cylinder of an engine and an intensifying means within said chamber, a flange upon said body member, adjacent to but away from one end 85 terminal of said intensifying means and providing a final and particularly short path for the current.

3. A device of the character described 90 comprising a body member having a chamber therein, intensifying means within said chamber, said intensifying means consisting of an insulating member, a plurality of metallic members in spaced relation therewith, and extending therethrough means for passing current to one said metallic member and a flange upon said body member and adjacent to the last successive metallic member 95 for receiving said current.

Signed at the city, county and State of 100 New York, this 19th day of September, 1923.

JOHN M. CLARK.
